GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY

CABLE CONNECTER

Application filed January 22, 1924. Serial No. 687,788.

The invention relates to combination cable connectors and outlet boxes, and more particularly to improvements in the construction of connectors for use in anchoring electric cables or conduits to electric fixture boxes, such as outlet boxes, switch boxes, cable boxes, and the like.

An object of the invention is to produce a connector employing one screw only, which does not engage the cable, but which performs the double purpose of simultaneously anchoring a connector in the box and gripping a cable in the connector.

An object of the invention is to produce an improved cable connector of split or separable design capable of being manufactured at low cost and which positively functions to securely fasten a cable to a box, as well as produce a cable connector which fits standard round knock-out holes in boxes of present-day use; and one important feature of my connector resides in the fact that it possesses means for engagement with a wall of the box, as the bottom thereof, for clamping together the two split connector sections with the cable therein between as well as for fastening said connector in the box knock-out opening.

The accompanying drawing illustrates an embodiment of the invention serving to illustrate the principle and structure thereof as well as the mode of operation; and modifications may be made without departing from the scope and principle of my invention.

Figure 1 shows a top open view of an electric fixture box joined to a cable through the agency of the improved connector constituting an important part of this invention; and Figure 2 shows an end view thereof.

Figure 3 illustrates a sectional view taken on the line 3—3 of the drawing; and Figure 4 shows a sectional view taken on the line 4—4 of the drawing.

Figure 5 illustrates a cluster view of the two-part connector showing rear, side, and top projections thereof.

To those conversant with the art, it is appreciated how present-day boxes B are made with standard round knock-out holes H into which the cable C carrying wires W is fastened by connectors; and as aforesaid it is

one of the principal objects of this invention to produce simple and inexpensive connectors for fastening the cable in the knock-out openings H of the box B.

With reference to the structure of the cable connector itself, it is observed that the said connector is made in two sections and constitutes mating half-cylindrical parts such that when placed together a sleeve is formed into which the cable is introduced. The cable retaining sleeve constitutes a cylindrical part split or separated on a plane parallel to the sleeve axis thus forming an upper-half sleeve 8 and a lower-half sleeve 9. Both sleeve parts 8 and 9 are made with a rib 10 on one part, and a rib 11 on the other part. This rib 10—11 encircles the sleeve and serves to abut the box wall when the parts are assembled; and preferably I provide an eccentric shou- 55 dering portion 13 on one of the sleeve parts as 60 at 9 which forms one wall of the groove 12 while the other rib 11 forms the other wall of the groove. This shoulder 13 is preferably made eccentric to the sleeve axis so as to permit the connector to be more readily placed 65 in the box opening. The box hole edge groove 12 is provided to receive the edge of the box hole and forms what may be termed box hole 70 edge abutment means or connector anchorage means because the connector is anchored in 75 the box thereby or is anchored in the box hole by other suitable means.

The structure of the cooperating parts is such that the upper sleeve section 8 is smooth from the rib 10 to the outer end thereof while 85 the sleeve part 9 differs in that it is made with the groove 12 and eccentric shoulder 13. On the forward end of each connector part 8 and 9 there is provided a bushing 15 against which the cable C rests and the wires W there- 90 of pass through when cable is fastened to the connector and box.

Ears 17 project from each sleeve part 8 and 9, and a screw 18 slides freely through one part, as the upper section 8 in this instance, while it is screw threaded to the ear of the lower ear and sleeve part 9. Thus the upper section 8 may slide up and down on the screw 18. The lower section 9 of the sleeve 95 may include a leg or lifting nose 19 which is 100

adapted to rest on the bottom of the box and produces an upward thrust on its integral connector sleeve half section 9 when the substantially long screw 18 is screwed downwardly.

5 The structure of the sleeve 8-9 may also include a cooperating shoulder 7 made in each half sleeve portion. Each section may have two shoulders, one in each wall and in alignment with the shoulder of the companion sleeve, the arrangement being such that the shoulder edges 7 slide into engagement with each other and serve to restrain both sleeve parts against longitudinal displacement and improves the holding ability of the connector when assembled in a box with the cable.

10 In assembling the parts, the connector sleeve 8-9 is inserted in the box knock-out hole H with groove 12 placed over the box wall and the rib 10-11 in engagement with the inner surface of the said box wall. The connector readily passes into the box opening H since it is inserted without the cable, for the parts are brought together which make it 15 smaller than the box hole H. The screw 18 and lifting leg 19 are set at an angle to the box wall bottom as shown in Figure 4, thereby causing the parts to fit loosely in the box hole when first inserted, and the cable is then 20 inserted in the sleeve. The shoulders 7 of each part cooperate to facilitate the lining up of the two sections in the box hole thus enabling the mechanic to quickly insert the connector, and by turning the screw 18 downwardly against the box wall B; the lower section 9 is lifted upwardly by both the screw 18 and lifting leg 19, and the screw extends itself as the lower part 9 lifts upwardly thereby 25 maintaining pressure against the box wall 30 despite the fact that said part 9 is moving away from the box wall surface against which the leg 19 is bearing. The bottom of the screw and leg rub or slide along the box wall until they both reach substantially a 35 vertical position. The upward pressure or thrust exerted through the screw and leg by the time vertical position is reached, forcibly 40 grips and clamps the lower sleeve 9 against the cable C, and in turn jams the cable against the upper part 8 as well as tightly presses the 45 sleeve part 8 against the box hole edge H to fasten the cable connector in the box.

50 Furthermore the action of the screw imparts a rotary motion to the sleeve causing it to secure a positively seated engagement with the knock-out box hole. As the screw 18 functions to draw upwardly on the lower sleeve part 9 resultant to the rotation of the entire sleeve and resultant to the upward 55 thrust produced by the leg 19, the eccentric shoulder 13 maintains its bearing engagement with the surface of the box wall, and rigidly restrains the sleeve from slipping from the hole H of the box in one direction, while 60 the shoulder 10-11 prevents it from moving 65

in the other direction; and thus the connector and cable are rigidly secured to the box.

It is observed that I have produced a connector employing one screw only for performing both essential functions, in that the 70 operation of the screw alone and by itself forces the box hole edge abutment ribs, particularly rib 10 or other suitable connector anchorage means, to overreach the box hole edge to anchor the connector against longitudinal displacement and to cause one sleeve 75 section, the part 9, to press toward the other one 8 which grips the cable in the connector. Furthermore the screw 18 itself is substantially long, it is mounted in one side of the 80 connector where it is convenient to reach with a screw driver and its end bears on the box wall beneath the sleeve.

In other words, the rotatable member 18 mounted to rotate in the connector, first acts 85 to move one part 9 of the connector sleeve laterally in the box hole toward the other part 8. This action grips the cable C between both parts and both parts are mounted in the box hole. Then follows further lateral motion of the entire connector, both parts 8 and 9, in and in relation to the box hole edge, the result of which is to seat the box hole edge 90 between the abutment means and thus anchor the connector against longitudinal displacement. 95

What I claim is:

1. Cable and box connecting means comprising, a box having a hole, a connector member embodying separable parts inserted into the box hole and receiving a cable therebetween, spaced abutment means on the connector between which rests the box hole edge, and means rotatably mounted on the connector cooperating with the box to move one 100 part toward the other to grip the cable and simultaneously move the connector laterally 105 in the box hole to seat one connector part against the hole edge.

2. Cable and box connecting means comprising, a box having a hole, a connector member embodying separable parts inserted into the box hole and receiving a cable therebetween, abutment means on the connector between which rests the box hole edge, said cable and box connecting means also comprising means for moving one of said parts toward the other to grip the cable and to move the connector laterally in the box hole to render the abutment means effective including a screw mounted on the first named part so as to bear against a box wall. 110 115 120

3. A cable and box connecting means as defined in claim 2 wherein a lifting leg is included on the part carrying the screw and is substantially parallel therewith, and the lifting leg moves against the box wall as the screw turns to aid in causing the aforesaid lateral motion. 125

4. Cable and box connecting means comprising, a box having a hole, a sleeve connector placed in the box hole and being split longitudinally to permit one end of the sleeve to expand to receive a cable and contract to grip the cable, spaced abutment means on the connector between which seats the box hole edge, said cable and box connecting means also comprising means for moving one of said parts toward the other to grip the cable and to move the connector laterally in the box hole to render the abutment means effective including a screw mounted on the first named part so as to bear against a box wall.
5. In combination with a box provided with a hole to receive a cable, of a connector to anchor the cable to the box, comprising a longitudinally split sleeve received into the 20 box hole and surrounding the cable, a leg formed on one sleeve bearing against the box and adapted to clamp together the split sleeve tightly around the cable, and means cooperating with the sleeve for sliding the leg along 25 the box wall to perform the said clamping operations and anchor the connector in the box.
6. In combination with a box provided with a hole to receive a cable, of a connector to anchor the cable to the box, comprising a sleeve longitudinally split to form two separable sections received into the box hole, means carried by one section bearing against the box wall, means carried by the same section bearing against the box wall for producing a rotary movement of the sleeve and a resulting thrust through the first named means for clamping the parts together, and anchorage means to fix the connector in the 40 box hole.
7. In combination, a box provided with a hole for the reception of a connector and cable, of a longitudinally split connector sleeve disposed in the hole, said sleeve split to form 45 separable parts, a rib encircling the sleeve and abutting the box wall on one side, a shoulder partly encircling the sleeve and abutting the box wall on the other side, a screw having connection with both separable parts by being 50 threaded into one part and loosely guided through the other part, a leg integral with one part standing parallel to the screw, the said leg and screw having their extremities seated against the box wall and at an angle 55 thereto permitting the said sleeve parts to separate to receive a cable, and said screw adapted to be turned against the box wall to force the parallel leg and screw into a position substantially right angular to the box 60 wall thereby anchoring all parts together.
8. A connector comprising, a longitudinally split sleeve including box hole edge abutment means, a leg and a screw upon one of said sleeve portions defined by the split engaging with a box wall to move said portion 65 laterally to clamp the cable and anchor the connector in the box hole.
9. A connector as defined in claim 8 where- 70 in the longitudinal split severs the sleeve and forms two parallel parts between which a cable is received, and the single screw is loosely mounted in one part, and is threaded into the other part, and the screw end is exposed to bear against a box wall to first move the screw threaded part toward the other to 75 grip the cable and moves both parts laterally in a box hole to establish sleeve anchorage.
10. A cable connector comprising, a sleeve composed of two parallel parts including box hole edge abutment means, a screw threaded 80 into one part on one side of the connector, and said screw end being exposed to engage a box wall to force the parts together and force the abutment means against a box hole edge.
11. A cable connector comprising, a sleeve 85 composed of two parallel parts including box hole edge abutment means, a screw disposed substantially normal to the general dividing plane of said parts and threaded into one part on one side of the connector, said 90 screw end being exposed to bear against a box wall to force the parts together and force the abutment means against a box hole edge, and a lifting leg substantially parallel with the screw, included on the part carrying the 95 screw, the end of the leg being adapted to engage a box wall and aid the screw in forcing the abutment means against a box hole edge.
12. A connector comprising a longitudinally split sleeve forming separable sections, a circumferentially directed rib made on one section, a circumferentially directed eccentric shoulder made on the same section and spaced adjacent the rib to provide a groove, a circumferentially directed abutment means on the other sleeve companion to the rib, a screw attached to one section and loosely working through the other, and a leg included on the section carrying the screw and parallel to the screw.
13. A cable connector comprising an arcuate body in the form of a cradle to support a cable, a leg extending from said body and engaging a box wall, a screw, threaded into the body cooperating with the leg to enforce lateral movement of the body to clamp the cable within the box hole and box hole anchorage means included on said body.
